Chesley L. Barr
ATTORNEY

UNITED STATES PATENT OFFICE.

JOHN F. BAKER, OF MANSFIELD, OHIO, ASSIGNOR TO WESTINGHOUSE ELECTRIC & MANUFACTURING COMPANY, A CORPORATION OF PENNSYLVANIA.

CAR-BOTTOM FURNACE-HEARTH SEAL.

Application filed June 25, 1927. Serial No. 201,420.

My invention relates to furnaces and more particularly to furnaces of the car-bottom type.

In the usual design of furnaces of the above-mentioned type, wherein the hearth is removable horizontally from the furnace chamber, difficulty has been experienced in providing a proper seal between the back wall of the furnace and the rear edge of the removable hearth to prevent the loss of heat therebetween.

It has been the practice to so construct the furnace that there is a relatively close fit between the rear edge of the hearth and the back wall of the chamber when the hearth is in operative position, thereby minimizing the loss of heat, but, quite obviously, such construction affords only an approximation of the desired result.

It is an object of my invention, therefore, to provide a sand-seal between the rear edge of a car-bottom furnace hearth and the back wall of the furnace chamber.

A further object of my invention is to provide a seal for the rear lateral edge of a longitudinally removable hearth which shall be automatically operable in response to movements of said hearth.

In practicing my invention, I provide, in a car-bottom furnace of the usual type, having a hearth longitudinally removable therefrom, a pair of cooperating channels supported upon the rear lateral edge of the hearth and the furnace wall, respectively, and adapted to cooperate automatically, as the hearth is moved into operative position, to provide a seal between the hearth edge and furnace chamber wall.

In the drawing:

Figure 1 is a view, in longitudinal vertical section, of a furnace embodying my invention;

Fig. 2 is a view, in section, on the line II-II of Fig. 1, and

Fig. 3 is an end elevation of the sand seal shown in Fig. 2.

Referring more particularly to the drawings, a furnace embodying my invention comprises a framework 2, of structural iron, supporting roof and side walls 4 and 6, of suitable refractory material, defining an open-bottom furnace chamber 8 having an opening in the front wall thereof to permit the insertion and removal of a movable hearth, as hereinafter described. The opening in the

front wall is closed by a door 10, in the usual manner.

A removable hearth 12, adapted to substantially fill the open bottom of the furnace chamber when in operative position, is of the usual car type and comprises a refractory hearth portion 14 mounted upon a pair of channels 16 which, in turn, are supported upon flanged wheels 18. Peripherally of the hearth and extending above the upper face of the hearth portion 14, are refractory walls 17, defining a shallow chamber for the reception of electrical-resistance heating elements 18.

The heating elements 18 comprise sinuously wound electrical resistors supported upon the upper face of the hearth portion 16 within the shallow chamber defined by walls 17.

A work-supporting plate 20, of suitable heat-resistant and thermally-conducting material, is peripherally supported upon the walls 17 and is reinforced intermediate its ends by refractory blocks 22 resting upon the upper face of the hearth portion 14.

Sand seals of the usual type are provided along the longitudinal edges of the car-bottom hearth (not shown) to prevent the loss of heat from the furnace chamber between the hearth and the side walls. An additional sand-containing trough 24 is formed on the front edge of the hearth and is adapted to receive a depending flange 26 on the lower face of the door 10, when the hearth and the door are in operative position, to seal the furnace-chamber entrance.

Additional means for heating the furnace chamber are provided, comprising sinuous electrical-resistance elements 28 supported upon the side walls thereof. The electrical connections for energizing the resistors 28, as well as resistors 18 on the movable hearth, may be made in any well-known manner and are, therefore, not shown.

The structure thus far described is common in furnaces of this type, and, since it forms no part of the present invention, further description thereof is not deemed necessary.

The means for sealing the rear lateral edge of the hearth comprises a channel 30, coextensive in length with the width of the hearth, supported upon the rear lateral edge of the movable hearth, and forming a trough for containing a quantity of granular refractory material. The arrangement is such that, with

the hearth in operative position within the furnace chamber, the sand trough is adjacent the back wall thereof and extends substantially the entire width of the chamber.

5 An inverted channel 34 is pivotally secured to the back wall of the furnace chamber by means of brackets 36 secured, at one end thereof, to the face of the channel and journaled, at the other end, on a rod 38 supported by the back wall of the furnace.

The pivoted channel 34 is so mounted that, when the hearth is in operative position, a flange 40 thereon depends into the trough formed by channel 30, and the rear flange 42

15 of the pivoted channel is between the rear flange of channel 30 and the back wall of the furnace chamber.

With the channel in operative position, as described, the rear longitudinal face thereof 20 is jammed against a metal plate 43 embedded in the furnace wall to minimize the clearance between the wall and the pivoted channel 34.

The pivot rod 38 is extended through and beyond the side wall of the furnace, and a 25 weight arm 44 is suitably secured thereto, outside the furnace chamber, to provide a support for a counterweight 46 adjustably secured thereto. The counterweight is secured to the arm 44 at such point that the channel 30 34 is normally maintained in raised position, as indicated by broken lines in Fig. 3. The downward movement of the counterweight 46 and the consequent upward movement of the channel 34 are limited by a stop 45 projecting from the side wall of the furnace which limits the movement of the arm 44 35 downwardly in a vertical direction.

In operation, the door 10 of the furnace chamber is raised or removed to permit the 40 hearth to be moved into the furnace chamber. As the hearth approaches the limit of its inward movement, the outer flange of the sand trough 30 engages the flange 42 of the channel 34, and, upon continued movement of 45 the hearth, the flange 42 is forced against the furnace back wall, thereby moving the flange 40 down into the refractory material in the sand trough, against the action of counterweight 46. The rear edge of the hearth is 50 thereby effectively sealed, and the door 10 may be closed and the heating elements energized.

Upon the removal of the hearth, the reverse action takes place. As the hearth moves 55 outwardly, flange 40 of channel 34 is automatically raised, in response to the action of the counterweight 46, and the sand seal is broken.

While I have shown a car-bottom furnace 60 of a specific type, quite obviously, my invention is applicable to furnaces of any type employing movable hearths. Also, it is clearly within the scope of my invention to vary the actual construction of the sand seal, as 65 well as the sealing material used. For ex-

ample, the channel 30 may be filled with a plastic or a liquid material, depending upon the temperature to be attained in the furnace chamber.

By my invention, I have provided an efficient and automatically operable seal for the rear edge of a movable hearth which is positive in operation and rugged in construction and one that reduces to a minimum the loss of heat therethrough.

75 Various modifications may be made in my invention without departing from the spirit and scope thereof, and I desire, therefore, that only such limitations shall be placed thereon as are imposed by the prior art and 80 are set forth in the appended claims.

75 I claim as my invention:

1. In a furnace, the combination with a furnace chamber and a car-type hearth removably positioned therein, of a member of 85 trough shape extending across the rear edge of said hearth and substantially coextensive in length with the width thereof and adapted to contain a granular refractory material, and a flange coextensive in length with 90 said trough and pivotally supported by the rear wall of said chamber to cooperate with said trough when said hearth is in operative position to form a sand-seal.

2. In a car-bottom furnace, the combination with a furnace chamber and a horizontally removable hearth, of a seal between the rear edge of said hearth and an adjacent wall of said chamber comprising a sand trough carried by said hearth and a flange 100 pivotally secured to said wall, and means responsive to movement of said hearth for moving said flange into operative position with respect to said sand trough.

3. In a furnace, the combination with a 105 furnace chamber and a hearth horizontally removable therefrom, of a mechanically operable seal between said hearth and the back wall of said furnace chamber, comprising a channel secured to said hearth adapted to 110 contain a quantity of granular refractory material, and a flange pivotally secured to said wall and adapted to cooperate with said channel, and means responsive to the movement of said hearth to move said flange into 115 and out of cooperation with said channel.

4. In a car-bottom furnace, the combination with a furnace chamber and a hearth removable through the front wall thereof, of a sand-trough carried by the rear edge of 120 said hearth and a flange carried by the back furnace wall positioned to depend into said trough when said hearth is in operative position, and means operable upon the movement of said hearth for raising said flange to 125 permit removal of said hearth.

5. In a furnace, the combination with a furnace chamber and a removable hearth therefor, of co-operating means on said hearth and a wall of said furnace chamber to 130

form a seal therebetween, means responsive to the movement of said hearth into said furnace for moving the elements of said sealing means into operative, interlocking relation, 5 and means responsive to the movement of said hearth out of said furnace for moving said elements out of operative relation.

6. A mechanical seal comprising a laterally movable trough adapted to contain a 10 refractory material and an inverted channel pivoted for lateral movement to cooperate therewith, counterweighted means for biasing said channel out of cooperation with said trough, and means responsive to the movement of said trough toward said channel for 15

forcing said channel into cooperation with said trough to form a seal.

7. In an automatically operable sand seal, a laterally movable sand trough, a pivotally mounted inverted channel having one longitudinal flange thereof adapted to depend into said sand trough, means for normally maintaining said flange in raised position out of said trough, and means whereby, upon movement of said trough toward said channel, said flange is forced downwardly into said trough. 20

In testimony whereof, I have hereunto subscribed my name this 16th day of June, 1927.

JOHN F. BAKER. 25
